UNITED STATES PATENT OFFICE.

JOHN McLACHLAN, OF NEW ORLEANS, LOUISIANA.

WIND-MOTOR.

SPECIFICATION forming part of Letters Patent No. 259,569, dated June 13, 1882.

Application filed September 14, 1881. (No model.)

To all whom it may concern:

Be it known that I, JOHN McLACHLAN, of New Orleans, in the parish of Orleans and State of Louisiana, have invented certain new 5 and useful Improvements in Wind-Motors, of which the following is a specification.

My invention consists in a wind-wheel provided with a turret for gathering and directing the wind upon the wheel; also, in a vane-wheel combined with the turret for turning the same to the wind; and, further, it consists in certain novel features of construction, all as hereinafter described and claimed.

Reference is to be had to the accompanying 15 drawings, forming part of this specification, in which similar letters of reference indicate corresponding parts in all the figures.

In the drawings, Figure 1 is a vertical section of my improved motor. Fig. 2 is a horizontal section of the same. Fig. 3 is a vertical section of the turret at right angles to Fig. 1. Fig. 4 is a face view of the vane-wheel. Figs. 5 and 6 are detail sections.

The apparatus is supported upon a tower 25 consisting of pillars *d*, at the top of which are brackets *e*. The pillars and brackets are suitably braced, and on the brackets is fixed a ring or curb, *f*, that sustains the revolving turret *A*.

g g are wing-boards fixed on the brackets *e* 30 in an upright position and radially, and suitably braced at the top to form an inclosing frame for the turret. The turret *A* is a cylinder of sheet-iron, open at one side a distance somewhat less than half its diameter. To its lower edge is attached a cast-iron ring, *h*, in which rollers or wheels *i* are boxed, so as to support the cylinder. These rollers *i* rest on a ring-plate, *i'*, of metal, fixed on the curb *f*, which forms a track for the turret. On the 40 curb *f*, outside the turret, there are mounted rollers *k*, which impinge on the ring *h*, and at the top of the wing-boards are similar rollers, *k'*, that impinge on the outside of the turret, so that the turret is retained firmly in position. 45 Within the turret are curved plates *a*, preferably four in number, and forming wind guides or deflectors, that direct the current downward, as illustrated most clearly in Fig. 3.

C is the vane-wheel, sustained by suitable 50 bearings in a frame, *l*, fixed on the top of the turret. The frame *l* also sustains a short ver-

tical shaft, *l'*, on one end of which is a worm-wheel, *n'*, engaging a worm on the wheel-shaft, while the lower end of shaft *l'* carries a pinion, *m*, engaging a cogged rim, *m'*, that is fixed on 55 the inclosing frame of the turret. The wheel *C* is placed at the closed side of the turret, with its plane at right angles to the plane of the opening in the turret, with the effect that the vane-wheel, being turned by the wind, revolves shaft *l'*, and the pinion *m*, engaging ring *m'*, travels on the ring, and thus the turret is 60 revolved until the wheel *C* is edge to the wind and ceases to revolve, and the opening in the turret is presented squarely to the wind. This 65 action is automatic at all times.

B is the motor-wheel, which is of suitable construction, and sustained on a shaft, *o*, beneath the opening in curb *f*, where it receives the current of wind entering the turret and deflected downward by guides *a*. *p* are the revolving fans of the wheel. *q q* are fixed guides, curving from the center of the wheel outward on a cone *q'*, that is fixed over the center of the wheel. The guides *q* serve to give a circular 75 motion to the wind and direct it upon the fans *p*. For use when the wind is light, to gather the wind from an increased area, I provide the turret with sails *E* at the opposite sides and at the edges of the opening. 80

The construction is as follows: At the top of the turret arms *r* extend out horizontally to a suitable distance. On the outer edges of the wing-boards *g* are flanged or *T* plates *s*, which may be in either of the forms shown in larger 85 size in Figs. 5 and 6. The sails are canvas, and have attached to their inner edges loops *t*, that take upon the *T*-plates *s*, so as to slide thereon. The lower ends of the sails are attached to arms *u*, that are pivoted to the pillars *d* of the tower, so that when the sails are lowered the arms and sails may drop down against the pillars. To allow that movement the *T*-plates *s* are carried down to the pillars on curved supports *s'*. To the upper ends of 90 the sails bars *v* are attached, from which ropes *w* pass over friction-rollers *w'* or arms *r*, and downward to a convenient place for use in raising the sails.

It will be seen that I use a motor-wheel of 100 comparatively small size and concentrate and compress the wind upon it. The apparatus is

thus compact and not liable to be injured nor become unmanageable.

Having thus fully described my invention, I claim as new and desire to secure by Letters 5 Patent—

1. In a wind-motor, the combination, with the motor-wheel B, of the revolving turret A, provided with an opening at one side, and with the downwardly-curved deflectors a, and arranged above the said motor-wheel, substantially as and for the purpose set forth.

2. In a wind-motor, the combination, with the curb f, provided with the rollers k, and the wing-boards g, provided with rollers k', of the 15 turret A, provided with the rollers i, substantially as and for the purpose set forth.

3. In a wind-motor, the combination, with the frame l, the shaft l', the pinion m, the worm-wheel n', and the vane-wheel C, of the 20 turret A, provided with the cogged rim m', substantially as and for the purpose set forth.

4. In a wind-motor, the combination, with the wing-boards g, provided with the T-shaped brackets e, of the sails E, provided with the loops t, substantially as and for the purpose 25 set forth.

5. In a wind-motor, the combination, with the wing-boards g and the supports s', provided with T-plates, of the sails E, provided with the loops t, the arms u, the bars v, and the ropes 30 w, substantially as and for the purpose set forth.

6. In a wind-motor, the combination, with the revolving turret A, provided with the deflectors a, of the motor-wheel B, provided with the fans p and the fixed curved guides q, arranged below the said turret, substantially as 35 and for the purpose set forth.

JOHN McLACHLAN.
